EINAR GUSTAF EVALD HOGNER, OF STOCKHOLM, SWEDEN

HULL OF SHIPS

Application filed January 15, 1929, Serial No. 332,577, and in Sweden January 26, 1928.

This invention relates to improvements in propeller-driven ships having hulls of ordinary shape, and the primary object of the invention is to bring about in such ships a uniform distribution of the wake around the propeller axis.

To this end, the run of the ship is provided with at least one submerged bulb-shaped projection surrounding the propeller axis, and an after-body extending lengthwise beyond said projection, and further with a bending in between the projection and the after-body, said bending in separating said parts to such an extent as to leave the projection entirely free for the greater part of its length.

The said projections may as to their shape coincide substantially with the shape of one or more bodies of revolution which may be flattened or modified in other respects or their form may be totally different from a form of revolution. Moreover, where a plurality of bulb-shaped projections are provided, the bottom of the ship between the said 25 projections runs in a uniformly rising curve or line from the keel and upwardly toward the level water line, in order to facilitate a soft streaming off of the water from the hull of the ship, and also by adaptation of the 30 curves or lines between the projections with respect to each other and in relation to the shape and size of the said restrictions or channel-shaped formations to bring about suitable circulation of the water around the 35 said bulb-shaped projections. For the same purpose it is suitable to provide helically arranged guide surfaces, ridges, wings or blades, on the said bulb-shaped projection or 40 projections, preferably at some distance in front of the hindmost end of the said parts with a propeller provided thereat if desired. Thus a twofold advantage is obtained; in the 45 first place the guide surfaces will be situated in a stream which is not directly actuated by the propeller, so that the frictional losses will be smaller, and, secondly, the guide surfaces for a given desired circulation only have to give the water a comparatively small 50 tangential velocity.

Some embodiments of the invention are disclosed in the accompanying drawings.

Figs. 1-3 illustrate the after-body of a ship with one propeller, while Figures 4-6 show the after-body of a ship provided with two 55 propellers. In the drawings, Figs. 1 and 4 represent elevations with the longitudinal sections I and II while Figs. 2 and 5 show the section lines 0-8, and Figs. 3 and 6 the water lines 1-3 and the load water line 60 L. W. L. All these section lines are in all figures designated by the same numerals. Figs. 7 to 15 show modifications of the bulb-shaped projections. Fig. 16 shows the invention applied to an air-ship. 65

The drawings show how the after-body is formed at *a* on the lines of a bulb-shaped projection—here a cone with the apex directed aftwardly—the axis of which coincides with the propeller axes and at the apex of 70 which the propeller is provided. Ahead the mantle surface of the conical part passes over by degrees into the ordinary form of a ship. In Figs. 1 and 3, another shape with a curved generatrix is also indicated by dotted lines *b*. 75 In Fig. 4, line *d* represents the shape with which the bottom of the ship between the two conical parts *a* is extended from the keel and upwardly toward the load water line. At *f* in Figs. 1, 2, 4 and 5 is shown the channel-shaped formation in the surface of the hull of the ship, said formation extending here from the neighborhood of the bilge to the upper side of the conical parts *a*. In Figs. 1-3, a helically arranged guide apparatus in the 80 form of a ridge is indicated at *g*, and in Figs. 4-6 a guide apparatus in the form of a helically arranged blade is indicated at *h*, said guide apparatus being placed at some distance 85 in front of the propeller. For the sake of simplicity only one guide element is shown in both cases, it being obvious that they preferably are to be distributed uniformly about the propeller axis. Each kind of guide apparatus may evidently be used in ships having one 90 propeller as well as in ships having a plurality of propellers. 95

The mode of operation of the apparatus should be clear from the above description. By reason of the termination of the run of the 100

ship, which termination is one of rotational symmetry around the propeller axes, the wake current will be distributed about the propeller axes with better symmetry of revolution than with the ordinary shape of the run of a ship. It is possible however, that the wake having the best symmetry of revolution will be realized with another bulge form which in every case is to be designed, with respect to existing conditions. The channel formed between the bottom d of the ship and the conical parts a (see d in Fig. 4), in the embodiment provided with two propellers forms a favourable path for the water coming from the lower side of the bottom, and the upwardly directed streaming here will bring about circulation about the conical parts. By adapting the said channel and the channel-shaped formations f to each other the circulation may be modified to some extent, which may also be effected, to a greater extent, by means of the guide apparatus, as described hereinbefore.

Fig. 7 illustrates the after-body of a ship having a body of revolution similar to that one shown in Figs. 1 and 2, said latter body being here provided with a keel-shaped projection u at its under side for the purpose of obtaining a more favourable streaming of the dead water.

In the form of embodiment shown in Fig. 8 the projection a has in section the shape of a pear, and according to Fig. 9 the said projection is egg-shaped and, besides, obtains an unsymmetrical position relatively to the hull 35 of the ship, the bulb-shaped projection being helically twisted, as shown, in order to bring the water to circulate around the axis.

Figs. 10 and 11 illustrate arrangements of the projection a similar to those shown in Figs. 8 and 9, respectively, but applied to a ship having two propellers, the projection shown in Fig. 11 being somewhat twisted.

Figs. 12 and 13 illustrate an embodiment similar to that one shown in Fig. 7, the keel-shaped projection u being, however, in this case provided with a bulb v giving the streaming of the dead water a suitable distribution. The bulb v extends aftwardly and forms a support for the stern post p carrying the rudder r .

Fig. 14 illustrates a similar arrangement applied to a twin-screw ship.

Fig. 15 illustrates the fore-body or entrance of a ship having a bending in at w , similar to the bending in at the after-bodies shown in Figs. 1, 4 and 13, and having, besides, a cylindrical projection a ending in a calotte, said projection forming a bearing for the propeller.

Finally, Fig. 16 shows the invention applied to an air-ship, the projection a forming part of the hull proper and supporting the propeller shaft.

Obviously, the invention may also be car-

ried into effect in other ways, agreeing in principle, however, with the appended claims. The bulge-formed projections may be given different shapes, the same being generated, for instance by generatrices of different shape or said projections may be given shapes built up on the lines of modified bodies of revolution or from forms differing totally of the true form of revolution. Their number may also be greater than two, for instance in the case of a greater number of propellers. It is conceivable that the formation of an after-body in accordance with the invention is used even if no propellers are provided. Obviously, the invention also comprises a construction where the overhung after-body or stern k is supported further aftward than indicated in the drawing, by the part a by means of special supports, or by the parts a being to some extent built together with the part k . In ships provided with a plurality of propellers similar supporting or similar building together may also be made use of. In these cases, however, the free part of the bulge-shaped projection must extend far enough to cause a streaming having rotational symmetry at the end of the said projection. The guide apparatus may be given different shapes and dimensions, the ridges being, for example, made wider or longer than indicated in the drawing, and their position being altered within the scope of the invention. Otherwise, the construction of the after-body is arbitrary; for example, the curve d may extend horizontally immediately underneath the level water line, said curve indicating a horizontal flat bottom in the aft-most portion of the after-body. Rudders of any suitable construction may evidently be provided, with or without a lower support of constructional members projecting from the bulge-shaped projections or from other parts of the after-body.

What I claim is:—

1. In propeller-driven ships having a hull of ordinary shape, the provision on the run of the ship of at least one submerged bulge-shaped projection surrounding the propeller axis, an after-body extending lengthwise beyond said bulge-shaped projection, and a bending in between said projection and said after-body, said bending in separating said parts of such an extent as to leave the projection entirely free to the greater part of its length and said projection having such a shape as to bring about a uniform distribution of the wake around the propeller axis.

2. An arrangement according to claim 1, characterized by the submerged bulge-shaped projection having a keel-shaped appendix at its lower side.

In testimony whereof I affix my signature.

EINAR GUSTAF EVALD HOGNER.
